ELIE MONEUSE AND LOUIS DUPARQUET, OF NEW YORK, N. Y.

Letters Patent No. 85,468, dated December 29, 1868.

COOKING-RANGE.

The Schedule referred to in these Letters Patent and making part of the same.

To all whom it may concern:

Be it known that we, ELIE MONEUSE and LOUIS DUPARQUET, of the city and State of New York, have invented and made a certain new and useful Improvement in Cooking-Ranges; and we do hereby declare the following to be a full, clear, and exact description of the said invention, reference being had to the annexed drawing, making part of this specification, wherein—

Figure 1 is a longitudinal section of said improved range;

Figure 2 is a cross-section at the line *x x*;

Figure 3 is an end elevation; and

Figure 4 is a plan, with the top plate removed near one end.

Similar marks of reference denote the same parts.

This improved range is especially adapted for hotels, restaurants, and other places where there is a large amount of cooking, baking, broiling, frying, roasting, &c.; and

This range is constructed with special reference to facilitating the access of the cooks and attendants to all parts of the range, so that each may perform his duty without interfering with the other.

The nature of this invention consists in an arrangement of fire-chambers, ovens, and flues, so that the range has two fronts and an end, that can be employed for cooking-purposes, the attendants having opportunity to stand all around the range. The products of combustion are utilized in heating ovens or spaces for warming plates, and keeping the cooked viands warm, and the escape-gases are taken off from the central part of the range, either upward or downward, to a chimney.

In the drawing—

a and *b* are the front plates;

c, the end plate; and

d, the top plate of the range.

In this plate *d* the usual and desired holes are provided, for the reception of pots or other vessels, or for frying-pans or gridirons.

The square covers, at *e*, are adapted to frying-pans, and the shelf *f*, running along over the middle part of the range, is convenient for temporarily supporting any dish or other article that may be in use.

The fire-chambers are arranged on the two sides of the range, as at *g g*, *h h*, and at the end, at *k*.

Each fire-chamber is provided with a grate and ash-pit, as usual, with the proper doors, fire-bricks, &c.; and the fire-chambers are arranged opposite to each other, one on one side of the range, and the other on the other side.

The baking or roasting-ovens *i i* are located at the sides of the fire-chambers, and heated by flues that pass around them, and go off, at the back, by the respective flues *o o*, that occupy a space in the middle of the range.

The pipes *l*, leading from these flues *o* to a chimney, may pass off either above or below the range. We have shown them as passing away beneath the floor.

The warming-ovens or chambers *n n* are located further away from the fire than the ovens *i i*, and hence only receive the heat necessary for the intended

object, by the smoke-flue passing on one side, or by the heat radiated or conducted to the same from the other parts of the range.

The fire at the end *k* of the range is between two ovens, *i i*, and, beneath these, are ovens or warming-chambers, and the small ovens or warmers *n n* are also placed behind these ovens *i*, between those and the ovens *i* that are heated by the first of the side fires.

The usual water-backs may be introduced, with pipes and cocks, at the ends of the range, or at other convenient points, so as to furnish hot and cold water, and we prefer to set the fires some little distance back from the respective fronts of the range, so that the front plates themselves do not become very hot.

At the end of the range, we provide a boiling-apparatus, beneath which are receptacles, *m m*, for fuel, &c.

The broiling-grates *r* are set above the fire-spaces *s s*, and between the side plates *t t* of the apparatus, and covers *u u* are provided to slide down, and keep in the fumes from the broiling viands. These covers are counterbalanced, so as to slide freely.

v v are the escape-flues, and

w w are warming-closets between the broilers.

y y are plate-racks or warmers, above the broilers. This arrangement of range is a great convenience in large hotels, or where considerable cooking has to be done, and it will be apparent that this range could be extended in length by the addition of more fire-spaces and ovens.

In our range, the heat is kept within the range as much as possible, and one fire aids another, so that the action is equalized throughout the range to a considerable extent, so that the cooking-operations are not delayed when fresh coal is supplied to one fire. As a consequence, there is a great saving of fuel, and the range is very convenient for access all around it, so that there is no unnecessary loss of time with attendants.

What we claim, and desire to secure by Letters Patent, is—

1. A cooking-range, in which two rows of fire-spaces and ovens are arranged, substantially as set forth, so that the products of combustion pass away from the middle of the range, between said rows, as set forth.

2. The end fire-space *k*, with ovens on each side, arranged substantially as shown, in connection with the two rows of fire-spaces *h h*, and ovens *i i*, as set forth.

3. The warming-ovens or closets *n n*, placed below or between the ovens *i i*, so as to be of a lower temperature than said ovens *i*, the respective ovens being arranged substantially as set forth.

4. The broiling-spaces, arranged with the warming-closets between them, and the racks or shelves *y* above, substantially as set forth.

In witness whereof, we have hereunto set our signatures, this 8th day of September, 1868.

E. MONEUSE.
LOUIS DUPARQUET.
